UNITED STATES PATENT OFFICE

CHESTER A. BACON, OF AUBURN, NEW YORK, ASSIGNOR TO BOWEN PRODUCTS CORPORATION, OF AUBURN, NEW YORK, A CORPORATION OF NEW YORK

LUBRICATING SYSTEM

Application filed April 23, 1925. Serial No. 25,257.

This invention relates to a new and improved tank and pump and more particularly to a combined tank and pump formed of pressed steel, and especially designed for 5 chassis lubrication.

In a structure of this character in which the pump cylinder is secured to the bottom of the tank, as by riveting, and the plunger or piston moves through the upper wall or 10 cover of the tank, and the piston or plunger of necessity has a close fit in the bore of the cylinder, it is, owing to variations in riveting and the general spring present in sheet-metal work, found practically impossible to 15 maintain accurate alignment of the piston with the pump cylinder, which is required if the piston is to move in the cylinder without sticking or jamming.

One of the objects of this invention resides 20 in an adjustable or floating bearing which permits the piston to automatically align itself with the pump cylinder to compensate for any ordinary variations existing in or produced by handling or otherwise in the 25 manufactured product.

A further object resides in the provision 30 of means in combination with the floating bearing or button for preventing the escape of oil from the bearing, and for wiping the piston to remove oil from its surface as a portion of the piston moves out of the tank on the return stroke.

A further object resides in the provisions 35 of means for preventing the escape of lubricant through the joint between the cover and the body of the tank.

A further object resides in the provision 40 of a novel form of bracket for securing the tank and pump to a suitable support as an automobile frame.

Other objects and advantages relate to the 45 details of the structure and the parts thereof, all as will more fully appear from the following description, taken in connection with the accompanying drawings, in which:

Figure 1 is a top plan view of the structure, with portions broken away and other portions shown in section.

Figure 2 is a vertical section on line 2—2, 50 Figure 1.

Figure 3 is a sectional view of the lower end of the pump cylinder showing the leads therefrom.

Figure 4 is a view of a section of the sleeve member utilized for producing an oil-tight 55 joint between the body and cover of the tank.

Figure 5 is an elevation of the tank showing the bracket secured in place.

Figure 6 is a perspective view of the sleeve carried by the piston. 60

Figure 7 illustrates a modified form of floating button or bearing.

The structure as here illustrated comprises a tank consisting of a cover —14— and a cup-shape substantially cylindrical tank 65 body —1— having a substantially central opening in its bottom wall through which the reduced upper end portion of pump cylinder —2— extends, the inwardly projecting portion of which reduced end is riveted 70 outwardly at —3— into contact with the inner surface of the bottom wall of the tank body so that in effect the wall of the tank is tightly and rigidly confined in a circumferential channel in the outer surface of the 75 cylinder —2—.

The bore of cylinder —2— has its upper portion —4— accurately shaped and finished so that piston —5— has a very tight fit within this portion of the bore of the cylinder, while the bore of the lower portion —50— may be somewhat enlarged to permit in the process of manufacture the accurate finishing of the bore of the part —4— without excessive expenditure of time, labor and material. The 80 lower end of cylinder —2— may, as shown, be externally threaded for cooperation with an internally threaded two-way fitting —6—, which may, as here shown, have lubricant 85 conveying tubes —7— secured to it in any suitable manner, as by tubular compression nuts —9—. The lower end of the cylinder —2— is internally threaded for the reception of an externally threaded headed plug 90 —8— formed with a vertical passageway —10— leading to a lateral passageway —11— forming means of communication between the bore of cylinder —2— and the lubricant conveying tubes —7—. Screen —12— may 95

100

be carried by the plug —8— in the manner shown when desired.

The piston or plunger —5— has its lower end normally positioned within the upper end of the cylinder —2—, and in order to permit flow of lubricant from tank —1— into the cylinder, the lower end —13— of the piston is reduced in size as by flattening it upon opposite sides, as illustrated. The piston —5— extends upwardly through an opening in the cover —14— and in order to permit the piston to automatically align itself with the bore of cylinder —2—, this opening is made considerably larger than the diameter 15 of the piston, and is equipped with a floating button or bearing —15—.

The at present preferred form of the button as shown in Figure 1 consists of a cylindrical sleeve —16— of considerably less diameter than the opening through the cover —14— of the tank —1—, the sleeve being arranged in the opening and having its upper edge formed with an outwardly extending flange —17— and its lower portion formed with an outwardly extending flange —18— preferably as illustrated spaced from the flange —17— a distance somewhat greater than the thickness of the cover —14— so as to form a circular groove or channel of 30 a width somewhat greater than the thickness of cover —14— but adapted to receive the edge of the cover surrounding the opening through which the piston —5— extends, and for the purpose of normally maintaining the 35 button or sliding bearing in any position which it may assume an annular disk —19— of spring steel or other suitable material is provided with its outer edge in contact with the upper surface of the cover —14— and its inner edge bowed away from the cover and 40 in contact with the inner surface of flange —17—, whereby the tension of the annular spring disk —19— is such as to frictionally maintain the floating bearing in any assumed 45 position to prevent rattling, etc.

The outer end of flange —18— is returned inwardly so as to form an inwardly projecting flange —21— spaced from the flange —18— and forming an inwardly opening circular groove or channel for receiving the outer edge of an annular disk shape packing or gasket —22— through which the plunger —5— extends, the opening through the packing being preferably of approximately the 55 same size or slightly smaller than the diameter of the piston rod —20— so that as the piston rod moves through the packing any oil clinging to the surface of the rod is wiped off by the packing and retained within the tank.

As shown, the opening through the packing is of less diameter than the external diameter of the piston rod, and the inner edge of the packing is deformed downwardly as 65 illustrated so as to tightly grip the rod, and

this portion of the packing is re-formed at each operation of the piston rod by means of a sleeve —23— secured to the piston rod in any suitable manner as by rivet or pin —24— extending thru the sleeve and rod, the upper end of the sleeve being formed with a head —25— having a beveled surface —26— forming a tapered recess adapted to receive the downwardly inclined inner edge of the packing —22— and re-form it after it has been 70 opened out by the down stroke of the piston rod. Preferably the enlarged head —25— is formed with radial grooves —27— leading to the tapered recess —26— to permit the escape of any lubricant therefrom. The diameter of the head —25— is approximately the 75 same as or slightly less than the internal diameter of the flange —21—.

It will be obvious from this disclosure that the bearing described is capable of automatically adjusting itself within the limits of the size of the opening through the cover —14— under automatic actuation by the piston rod —5— in aligning itself with the bore —4— of cylinder —2—. Spring —51— is provided 80 surrounding the piston —5— and confined between the bottom of tank —1— and the head —25— of sleeve —23— so as to normally return the piston to its uppermost position and return it in such position ready 85 for manual actuation.

For the purpose of securing the cover —14— to the tank body —1—, the outer surface of the upper edge of the tank body is formed with a circular groove, and at portions around its periphery the downwardly flanged edge of cover —14— is pressed inwardly to form indented parts —28— which seat in the cooperating groove in the surface of the tank body to permanently secure the 100 parts together, and for the purpose of preventing the escape of oil between the cover —14— and the tank body —1—, a circular sleeve —29— of tin or other suitable material is arranged within the upper edge of the 105 tank body —1—, the sleeve being formed with a beaded part in the form of an outwardly extending flange —30— and an inclined upwardly and inwardly extending flange —31— which is adapted to be sprung 110 pressed toward the flange —30— so as to lie substantially parallel with the flange —30—, as perhaps best illustrated in Figure 2 when the cover —14— is assembled with the tank body, whereby a tight joint is formed which 115 prevents the escape of oil between the cover and the tank body.

Any suitable means may be provided for refilling the tank from time to time, as for instance, a filling opening normally closed 120 by a threaded cap —32—.

In Figure 7 a slightly modified form of floating button is shown in that instead of the spring disk —19— an angle bar —33— is made use of, one flange —34— of said bar 130

lying in and fitting the channel between the flanges —17— and —18—, and the other flanges —35— extending radially outwardly substantially parallel with the flange —18— and spaced from the flange —18— a distance substantially equal to the thickness of the cover —14— so that a channel is formed between the flanges —35— and —18— adapted to receive the edge of the cover about the opening 5 for the bearing, whereby floating or lateral sliding movement of the bearing is permitted within limits defined by the external diameter of the flange —34— and internal diameter of the wall of the opening in the 10 cover —14—.

For the purpose of supporting the tank in any suitable position, a bracket —36— of novel form is provided, and as perhaps best illustrated in Figure 5, is of substantially triangular conformation having two bolt openings —58— at its upper portion and a third bolt opening —58— at its apex or lower portion. The bracket, as shown, is formed of a single piece of sheet metal cut and shaped to 25 the configuration shown and spaced from and secured to the wall of the tank body by flanges —39— shaped to fit the outer wall of the tank body and secured thereto in any suitable manner, as by welding, or the like.

Integral inwardly bent flanges —40— are provided adapted to engage the heads of the bolts —41— so as to prevent their rotation.

Altho I have shown and described a specific structure of combined tank and pump, and details thereof with particular reference to the specific structures of floating bearing, still I do not desire to restrict myself to the details of structures herein described as constituting at present perhaps preferred embodiments of my invention, as various changes and modifications may be made without departing from the spirit of the invention as set forth in the claims hereto appended.

I claim:—

1. A combined tank and pump comprising a receptacle and a pump cylinder secured thereto, a piston movable through a wall of the receptacle and in the pump cylinder, a bearing for said piston carried by the wall 50 of the receptacle, slidably laterally in all directions with respect to said wall, and including spring means tending to maintain the bearing in any position.

2. A combined tank and pump comprising a receptacle including a cover having an opening therethrough, a pump cylinder secured to the receptacle, a piston movable through the opening in the cover and in said pump cylinder, and a floating bearing for the piston mounted in the opening in the cover and comprising a sleeve of less diameter than the opening, and positioned in the opening and having outwardly extending flanges at its 65 opposite ends, one within and the other out-

side the cover to permit lateral sliding movement of the sleeve with respect to the cover.

3. A combined tank and pump comprising a receptacle including a cover having an opening therethrough, a pump cylinder secured to the receptacle, a piston movable through the opening in the cover and in said pump cylinder, and a floating bearing for the piston mounted in the opening in the cover and comprising a sleeve of less diameter than the opening, and positioned in the opening and having outwardly extending flanges at its opposite ends, one within and the other outside the cover to permit lateral sliding movement of the sleeve with respect to the cover, a return bent flange on the flange within the cover, and an annular gasket having its inner edge gripping the piston and its outer edge confined in the channel formed between the flange within the cover and the return bent flange. 70 75 80 85

4. A combined tank and pump comprising a receptacle including a cover having an opening therethrough, a pump cylinder secured to the receptacle, a piston movable through the opening in the cover and in said pump cylinder, a floating bearing for the piston mounted in the opening in the cover and comprising a sleeve of less diameter than the opening, and positioned in the opening and having outwardly extending flanges at its opposite ends, one within and the other outside the cover to permit lateral sliding movement of the sleeve with respect to the cover, a return bent flange on the flange within the cover, an annular gasket having its inner edge gripping the piston and its outer edge confined in the channel formed between the flange within the cover and the return bent flange, and a sleeve on the piston for re-forming the gasket after each 90 95 100 105 operation of the piston.

5. A combined tank and pump comprising a receptacle including a cover having an opening therethrough, a pump cylinder secured to the receptacle, a piston movable through the opening in the cover and in said pump cylinder, a floating bearing for the piston mounted in the opening in the cover and comprising a sleeve of less diameter than the opening and positioned in the opening and having outwardly extending flanges at its opposite ends, one within and the other outside the cover, said flanges spaced apart a distance greater than the thickness of the cover at the opening to form a circular outwardly opening channel and a disk seated in said channel and extending outwardly therefrom and engaging one surface of the cover and held in said channel by one of said flanges, and spaced from the opposite flange a distance substantially equal to the thickness of the cover. 110 115 120 125

6. A combined tank and pump comprising a receptacle including a cover having an 130

opening therethrough, a pump cylinder secured to the receptacle, a piston movable through the opening in the cover and in said pump cylinder, a floating bearing for the piston mounted in the opening in the cover and comprising a sleeve of less diameter than the opening and positioned in the opening and having outwardly extending flanges at its opposite ends, one within and the other outside the cover, and a disk formed of spring metal having its outer edge engaging the outer surface of the cover and its inner edge bowed away from the cover and engaging the inner surface of the flange outside the cover on said sleeve.

7. A combined tank and pump comprising a receptacle including a cover having an opening therethrough, a pump cylinder secured to the receptacle, a piston movable through the opening in the cover and in said pump cylinder, a floating bearing for the piston mounted in the opening in the cover and comprising a sleeve of less diameter than the opening and positioned in the opening and having outwardly extending flanges at its opposite ends, one within and the other outside the cover, to thereby form an outwardly opening circumferential channel, and an annular disk having its inner edge seated in said channel and its outer edge engaging the outer surface of the cover and spaced from the flange within the cover a distance substantially equal to the thickness of the cover.

In witness whereof I have hereunto set my hand this 13th day of April, 1925.

CHESTER A. BACON.
